UNITED STATES PATENT OFFICE

109,500

DESIGN FOR AN ACCORDION OR SIMILAR ARTICLE

Franklin Robbins, New York, N. Y., assignor to
New York Band Instrument Co., Inc., New York, N. Y., a corporation

Application January 26, 1938, Serial No. 74,574

Term of patent 7 years

To all whom it may concern:

Be it known that Franklin Robbins, a citizen of the United States and resident of New York city, in the county of New York, State of New York, has invented a new, original, and ornamental Design for an Accordion or Similar Article, of which the following is a specification, reference being had to the accompanying drawings, forming part thereof, and in which,

Fig. 1 is a perspective view of an accordion embodying my new design; and

Fig. 2 is another perspective view thereof.

I claim:—

The ornamental design for an accordion or similar article substantially as shown.

FRANKLIN ROBBINS.
